United States Patent Office.

JEREMY B. WARDWELL, OF GEORGETOWN, DISTRICT OF COLUMBIA.

Letters Patent No. 65,781, dated June 11, 1867.

IMPROVED WEATHER-STRIP.

The Schedule referred to in these Letters Patent and making part of the same.

TO ALL WHOM IT MAY CONCERN:

TO ALL WHOM IT MAY CONCERN: Be it known that I, JEREMY B. WARDWELL, of Georgetown, in the county of Washington, and District of Columbia, have invented a new and improved Weather-Strip; and I do hereby declare the following to be a full and exact description of the same, reference being had to the accompanying drawings, which are made part of this specification, and in which—

Figure 1 is a front elevation.

Figure 2 is a vertical transverse section.

Similar letters of reference indicate corresponding parts in the two figures.

Similar letters of reference indicate corresponding parts. The strip is formed of a plate of India rubber, and, with the springs bearing upon its upper surface, is attached to a horizontal rotating shaft, moved by the closure of the door, a stud on the door-casing impinging upon a lug on the shaft. The door is hollowed out to

upon a lug on the shaft. In the drawings, A is the door-casing; B the threshold; C the door, whose lower end is hollowed out to receive the strip and its operative devices. D is a horizontal shaft, having its bearings in the upturned ends of the plate E, which forms the lower edge of the door. This plate has an opening, through which the strip F projects when the shaft D is rotated by the contact of its lug G with the projecting stud H on the door-casing when the door is closed. When the door is opened the strip rises as the shaft D is rotated in the other direction by the springs I, which are connected by wires to lugs on the shaft D. The India-rubber strip F is clamped between plates K K, which are attached to the shaft D, and springs L L, &c., also attached to the shaft, bear upon the strip F near its edge, and press it down against the threshold and into any inequalities thereon, so that a knotty or uneven step will not permit the passage of the air in the hollows of the undulations. By this means the crevice or gap under the door will be thoroughly stopped, which cannot be the case with an uneven door-sill when a straight weather-strip is applied.

...sill when a straight weather-strip is applied, is my invention, what I claim as new, and desire to secure by Letters Patent, is

I claim the weather-strip, provided with the springs by which the elastic strip F is made to conform to the irregularities of the threshold, as herein described for the purpose specified. J. FREDERIC B. WARDWELL.

JEREMY B. WARDWELL.
